UNITED STATES PATENT OFFICE.

WILLARD E. SWIFT, OF WORCESTER, MASSACHUSETTS, ASSIGNOR TO UNITED STATES ENVELOPE COMPANY, OF SPRINGFIELD, MASSACHUSETTS, A CORPORATION OF MAINE.

RECEPTACLE FOR DRINKING-CUPS.

1,186,705.

Specification of Letters Patent. Patented June 13, 1916.

Application filed August 21, 1912. Serial No. 716,196.

To all whom it may concern:

Be it known that I, WILLARD E. SWIFT, a citizen of the United States, residing at Worcester, in the county of Worcester and 5 Commonwealth of Massachusetts, have made a new and useful Invention Relating to Receptacles for Drinking-Cups, of which the following is a specification accompanied by drawings forming a part of the same.

10 My invention relates to a receptacle for drinking cups adapted to hold a stack of drinking cups preparatory to their insertion in a distributing cabinet.

The object of my invention is to provide 15 means for maintaining the stack of drinking cups in proper position for distribution in the cabinet, and to provide means when the receptacle and inclosed stack of cups have been inserted in the cabinet, for releasing 20 the cups from the receptacle in order to enable them to be individually withdrawn. This result is accomplished by forming the receptacle with an opening at its lower end and providing a removable obstruction at 25 this opening to retain the cups within the receptacle until they have been inserted in proper position within the distributing cabinet. The obstruction may then be removed and the cups withdrawn through the openings 30 in the receptacle and cabinet as desired for use or, in some embodiments of the invention, the receptacle may be withdrawn from the cabinet if desired as soon as the cups have been inserted in proper position in the cabinet and before they have 35 been withdrawn from the cabinet for use.

A receptacle constructed in accordance 40 with my present invention is designed to be inserted in a distributing cabinet after having been filled with drinking cups, thereby serving to place the cups in proper position for withdrawal from the cabinet. The form of receptacle illustrated in the accompanying drawings and hereinafter described for 45 the purpose of illustrating the principles of my invention is particularly adapted for use in the distributing cabinet described in my copending application, Serial No. 681,582, filed March 4, 1912, cabinet for pa- 50 per drinking cups.

Referring to the drawings, Figure 1 represents a perspective view of the receptacle after having been filled with drinking cups and prepared ready for insertion in the dis- 55 tributing cabinet. Fig. 2 is a perspective

view of the receptacle before filling, showing the receptacle with its lid opened. Fig. 3 is a perspective view of the receptacle with the telescopic cover applied to close its open end. Fig. 4 is a sectional view of a distributing cabinet with the cup receptacle inserted therein, also shown in section. Fig. 5 is a vertical sectional view of the cabinet after the withdrawal of the receptacle therefrom.

Similar reference figures refer to similar parts in the different views.

The receptacle embodying my present invention consists of a rectangular box in cross section, preferably made of cardboard, 70 as represented in Fig. 2, having a bottom 1, sides 2 and 3, and a closed end 4. The opposite sides of the box at one end are beveled or chamfered at 5, 5, for the purpose herein-after set forth. To the outer side of the bottom, paper bands 6 and 7 are attached by their gummed ends. The receptacle is filled with drinking cups in an inclined position corresponding to the inclination of the beveled ends 5 of the box sides 2 and 3.

Hinged to one of the sides 2 of the receptacle by a gummed flexible strip of cloth or heavy paper is a cover 8 provided at its outer edge and at one end with the gummed strips 9 and 10. When the receptacle has 85 been filled with drinking cups as above described, the cover is closed and attached to the side 3 and end 4 of the receptacle by means of the gummed strips 9 and 10, as shown in Fig. 1. The bands 6 and 7 are 90 then attached to the outer side of the cover 8 by gum applied to their opposite ends. The bands 6 and 7 are thereby drawn taut across the drinking cups, which are held in place resting on the bands 6 and 7 when the 95 receptacle is placed in an upright position with its beveled end the lowermost in order to insert it in the cabinet, as shown in Fig. 4. The bands 6 and 7 are unyielding so that, until they are broken as hereafter de- 100 scribed, they will prevent passage of any of the cups through the opening at the bottom of the receptacle. The sides 2 and 3 project a short distance beyond the plane of the bands 6 and 7 in order to prevent the end 105 cup from being protruded over the sides. The receptacle and cups then constitute a package 11, as represented in Fig. 1, capable of being inserted endwise in a cabinet 12, with the chamfered or beveled end of the 110

receptacle lowermost. The cabinet 12 is provided at its lower end with hinged doors 13, 14, having a central opening 15 through which the operator is able to reach the bands 6 and 7, and forcibly sever the same allowing the stack of drinking cups 16 to fall downward against the hinged doors 13 and 14. The receptacle is withdrawn from the top of the cabinet and a weight 17 is placed 10 upon the top of the stack of drinking cups and the top of the cabinet closed by the cover 18.

The receptacle enables the entire supply of drinking cups carried to fill the cabinet 15 to be inserted by a single operation, with the drinking cups occupying an inclined position resting upon the hinged doors 13 and 14. The drinking cups can also be placed 20 in their proper position in the receptacle, thereby preventing any displacement which might arise from the carelessness of the operator in filling the cabinet direct.

As the receptacle may not be inserted in a cabinet immediately after filling, I inclose 25 the beveled end of the package 11 in a cover 19 which telescopes over the beveled end of the package, as shown in Fig. 3. This cover I preferably provide with an opening 20, smaller than the drinking cup, but large 30 enough to disclose any printed matter placed thereon. When the cover 19 is applied, a drinking cup is inserted between the bottom of the package 11 and the opposing side of the cover which serves, by its exposed in- 35 scription, to disclose the class of cups contained in the package.

I claim,

1. A receptacle for a stack of collapsed drinking cups, comprising a box having a 40 cross sectional area less than the area of one of said cups and having a beveled open end equal in area to one of said cups, to permit the broadside withdrawal of the lowermost cup therethrough, and removable means ex- 45 tending across said open end and secured to opposite sides of said box.

2. A receptacle for a stack of collapsed drinking cups comprising a box having an open end for the broadside withdrawal of 50 the lowermost cup therethrough, and a breakable band extending across said open end and secured to two opposite sides of said box, the other sides of said box being extended beyond the plane occupied by said 55 band.

3. A receptacle for a stack of collapsed

drinking cups comprising a box having a cross sectional area less than the area of one of said cups and having an open end for the withdrawal of the lowermost cups of said 60 stack, a band secured to opposite sides of said box and extending across said end to support the stack when the box is placed in an upright position, with each cup in an inclined position, and a detachable cover 65 for the open end of said box.

4. A package of collapsed drinking cups for insertion in a dispensing cabinet, comprising a box adapted to fit loosely in said cabinet and containing a stack of such cups, 70 said box having an opening at the end corresponding to the delivery end of said cabinet, and a breakable band secured to the box on opposite sides of said opening, for exposure by the delivery opening of said cabinet 75 when the package is inserted therein, whereby the breaking of said band permits the withdrawal of said box to leave the stack of cups in the cabinet.

5. A package of collapsed drinking cups 80 for insertion in a dispensing cabinet, comprising a box adapted to fit loosely in said cabinet and containing a stack of such cups, said box being open at the end corresponding to the delivery end of said cabinet, and 85 a breakable band secured to two opposite sides of said box and extending across said open end, for exposure by the delivery opening of said cabinet, the other sides of said box being extended below the plane occupied by said band.

6. A package of collapsed drinking cups for insertion in a dispensing cabinet comprising a box fitting loosely in said cabinet and containing a stack of such cups, said 95 box being beveled at the end corresponding to the delivery end of said cabinet and providing an opening in said beveled end for withdrawal of the lowermost cup, and removable means secured to the box and extending across said opening for exposure by the delivery opening of said cabinet when the package is inserted therein, whereby the removal of said removable means permits the withdrawal of cups from said cabinet. 100 105

Dated this seventeenth day of August 1912.

WILLARD E. SWIFT.
